UNITED STATES PATENT OFFICE

ERNEST E. HOWARD, OF KANSAS CITY, MISSOURI

VERTICAL LIFT BRIDGE

Application filed June 9, 1930. Serial No. 459,854.

This invention relates to improvements in vertical lift bridges and refers more particularly to a bridge span composed of trusses or girders and a floor for carrying whatever type of traffic the span is designed to support, such as railroad or vehicular traffic. The operation of the vertical lift is such that the span is raised and lowered in a vertical travel while the span is suspended in a horizontal 10 position.

Fig. 1 is a diagrammatic view of one of the supporting towers, including a portion of the lift span. Fig. 2 is a detail of a modified form of belt tightener.

15 In order to simplify the explanation and understanding of the invention, the mechanism on but one of the towers will be explained as the towers are identical in operation and construction. The numeral 1 designates the lift span, the numerals 2 the towers which support the span.

The span is suspended by suitable flexible supporting means preferably steel wire ropes such as are shown at 3. These wire ropes 20 run over the main supporting sheaves 4, rotatively mounted on the top of the towers which towers may be constructed of steel, timber, reinforced concrete, or other material. The flexible wire ropes 3 are attached to the lift span 1 and also to a counterweight 5. The counterweight on each tower is equal approximately in weight to one half of the weight of the span so that the counterweights balance the weight of the span.

35 For operating the span there are provided at the top of each tower driving pulleys 6 and 6A which are connected by trains of gears and pinions 7, 8, 9, 10 and 11 to the main sheaves on the tower. The pulley 6 is mounted upon the shaft 12, upon which is also mounted the pinion 8. The pulley 6A is mounted upon the shaft 12A upon which is also mounted the pinion 7. The pinions 7 and 8 mesh with the gear wheel 9. This latter 40 gear is mounted upon the shaft 13, which also carries pinions 10, meshing with the large gears 11, mounted upon the shafts carrying the sheaves 4. One drive pulley 6A through a flexible cable 29A and gear train 7, 9, 10 and 50 11 provides for rotation in one direction and

the other pulley 6 with its flexible cable 22 and gear train 8, 9, 10 and 11 for rotation in an opposite direction. In other words, the drive provided through pulley 6A raises the span while the drive through the opposite 55 pulley 6 lowers the span. The reversal of the drive for raising and lowering the span by means of the flexible cables is produced by the manner in which the cables 22 and 29 are made to pass beneath the separate sets of 60 idler pulleys so that one, the cable 29, is led from over the top of the drive pulley 6A under the pulley 21, while the cable 22 is led from over the top of the drive pulley 6 to pass over the pulley 18, mounted on shaft 17. 65 The reversal of one of the drive pulleys could also be produced by interposing an intermediate gear between either of the gears 7 and 8 which mesh with the gear 9.

70 It will be observed that if one drive pulley on the top of each tower is simultaneously rotated at the same speed they will cause the main sheaves 4 on both towers to rotate simultaneously and thus lift the suspended span and lower the counterweight, or by reversing 75 the direction by operation of the other pair of drive pulleys the counterweights are lifted and the span lowered. In order to provide a suitable source of power to effect the operation, there is placed on the lift span a motor engine or other suitable source of power designated by the numeral 14. On the shaft of the motor is mounted a pinion 15, meshing with the gear 16 which, in turn, is carried by 80 the transverse shaft 17. On this transverse shaft 17 are a plurality of pulleys 18, 19, 20 and 21, or a grooved drum. Flexible driving means, preferably steel wire rope, runs upon the pulleys; the drive from the pulleys 18 and 21 is transmitted to the tower mechanism which is herein explained while the pulleys 19 and 20 transmit the power to the drive mechanism mounted upon the opposite tower which is identical in operation 85 with the drive explained.

90 Two parts of the flexible wire rope 22 which passes over the pulley 18 are carried out to the ends of the lift span and there pass under idler sheaves 23, which are rotatively 95 mounted on the lift span by means of a stand- 100

ard or support 24. These two parts are then carried upwardly one part passing over the drive pulley 6, the other part over idler pulleys 25, 26, and 27, and under idler pulley 23, terminating as the part which passes over the top of the idler pulley 6. In a similar manner, the two parts of the wire rope 29 pass under the idler pulleys 30 and 31, the upper part passing over the drive pulley 6A and the lower part over the idler pulleys 32, 33 and 34, and under the idler pulley 35 to combine with the part passing over the drive pulley 6A.

It is evident that, if the lift span begins to rise, the distance between the drive pulleys on the lift span and the corresponding drive pulleys on the top of the tower will shorten by the amount of the lift of the span. To compensate for this shortening, the endless flexible wire ropes are passed under the idler sheaves 35 which are mounted upon the main counterweight 5 or, as shown in the modified construction in Fig. 2, to supplementary counterweights 5a, which are raised and lowered in wells formed in the main counterweight or otherwise independent of the main counterweight. From these idler sheaves 28 and 35 one side of the flexible ropes are passed over suitable idler sheaves movably mounted so as to provide for tension in the flexible ropes and to carry one side of each flexible rope in such a manner that it may be continued back to the drive pulley on the lift span.

In Fig. 1, at points 37 and 38 on the counterweight 5 are pivoted weighted arms, one extension of the arms carrying the weights 39, the other arm extensions carrying the idler pulleys 27 and 34. The pivoted weights 39 keep a constant tension upon the driving ropes 22 and 29.

In addition to compensating for the difference in distance between the drive pulleys on the lift span and the drive pulleys on the towers, the idler sheaves 28 and 35 and their counterweights afford a means for maintaining tension in the flexible driving ropes. As suggested, the provision for maintaining the tightness of these flexible belts or ropes can be made by suitable counterweights 5a. One means of providing for flexible rope tension is shown in Fig. 1 and a modified provision is shown in Fig. 2. In place of the two types shown, springs may be provided to take the place of the small counterweights or similar known mechanical means.

The flexible driving ropes are provided in one or more pairs for each tower. A single driving rope has been shown in order to simplify the disclosure and explanation.

In the drawings, the flexible driving rope 22 is arranged to operate the drive pulley 6 when the driving pulley on the span is moving in a clockwise direction as indicated by the arrow on the flexible belt. It will be

observed that this belt provides a continuous connection from the top of the drive pulley on the span to the drive pulley on the tower, and engages both these drive pulleys sufficiently to provide the necessary friction for operation. The means for maintaining tightness in the flexible rope is provided on the opposite part of the driving rope from the driving part.

For reversal of direction, the companion flexible driving rope 29 is provided. It will be observed that for the counter clockwise movement the driven part of the belt provides a continuous connection from the bottom of the driving pulley on the span to the top of the driven pulley 6A on the tower and the means for maintaining tension in the driving rope 29 is carried on the opposite part of the rope from the driving part.

There is thus provided from the driving pulleys 18 and 21 on the lift span a direct connection through the tight side or part of the flexible ropes for either direction of rotation through the driving pulleys 6 and 6A on the tower. Corresponding flexible belts or ropes are provided through similar driving pulleys on the drive shaft of the lift span running over similar driven pulleys mounted on the opposite tower.

It is evident by proper adjustment of these flexible driving ropes rotation of the drive shaft on the lift span will cause similar and equal rotation of the main sheaves on both towers, as the sizes of the pulleys and the driving connections are identical on both towers, providing thereby for the lifting and lowering of the lift span, evenly and uniformly.

In practice, the four drive pulleys 18, 19, 20 and 21 inclusive on the lift span can be constructed as separate pulleys or as a single drum with separate grooves and the flexible belts or ropes for raising and lowering the lift span may be in two or more pairs for each tower.

In previous practice with lift spans where the operating machinery is placed on the tops of the towers, it has been necessary to provide a separate motor or source of power on the top of each tower. The present design provides for the operation of the machinery on the tops of both towers simultaneously and synchronously from the single source of power on the lift span. Where a separate source of power is required on the top of each tower internal combustion engines cannot be employed, but with the single source of power on the lift span the power may be supplied by an internal combustion engine.

Other advantages of the design are readily apparent. In the first place, it will be noted that substantially all of the machinery and weight is removed from the lift span and placed upon the towers, the motor and driving pulleys and the deflector sheaves being

substantially the only machinery left upon the span. Furthermore, by positioning the driven machinery on the separate towers and driving from a single source on the lift span, 5 there is an equalization and uniform distribution of transmitted power so that the machinery on both towers operates alike and is accurately synchronized.

In the present design, by the use of the 10 tightening devices, there is maintained a constant tension upon the driving belts regardless of the varying distances of the pulleys on the lift span, and the towers. This compensation is brought about by the idler 15 sheaves and supplementary counterweights.

Furthermore, it is thought to be novel practice to raise and lower the lift span from a single source of power positioned on the lift span through flexible endless ropes or belts 20 transmitting power to operate the main sheaves on the tops of the two towers.

Suitable brakes, not shown or described, of simple and positive character for hand operation can be provided on the driving shaft 25 on the lift span to control the movement. Where separate motors or sources of power are required on the top of each tower no such simple and positive brakes can be used.

I claim as my invention:

30 1. In a vertical lift span bridge, the combination with supporting towers, of a lift span, a source of power positioned on the lift span only, driving means on the lift span and driven means on the towers, flexible connections 35 between the driving and driven means, whereby when said driving means is actuated said lift span will be operated.

2. In a vertical lift span bridge, the combination with supporting towers, of a lift 40 span, a source of power positioned on the lift span only, driving means on the lift span and driven means on the towers, flexible connections between the driving and driven means, whereby when said driving means is 45 actuated said lift span will be operated, and means for compensating for the variation in the distance between the driving means on the lift span and the driven means on the towers.

3. In a vertical lift span bridge, the combination with supporting towers, of a lift 50 span, a source of power positioned on the lift span only, driving means on the lift span and driven means on the towers, endless flexible connections between the driving and 55 driven means having driving parts and return parts whereby said lift span is operated when said driving means is actuated and means interposed in the return parts of the flexible means for compensating for the variation in distance between the driving and 60 driven means.

4. In a vertical lift span bridge, the combination with supporting towers, of a lift 65 span, a source of power positioned on the lift span only, driving means on the lift span

and driven means on the towers, endless flexible connections between the driving means and driven means, having driving parts whereby said lift span is operated when said driving means is actuated and return parts and means interposed in the return parts for 70 maintaining tension in the return parts of the flexible connections and for taking up any stretch of the flexible connections.

5. In a vertical lift span bridge, the combination which includes the span and supporting towers, a single power source and driving means on the span, driven means on the towers and flexible connections therebetween, whereby said lift span is operated 75 when said driving means is actuated.

6. In a vertical lift span bridge, the combination which includes the span and supporting towers, a single power source and driving means on the span, driven means on the towers and endless flexible connections 80 therebetween, whereby said lift span is operated when said driving means is actuated.

7. In a vertical lift span bridge, the combination which includes the span and supporting towers, a single power source and driving means on the span, driven means on the towers and endless flexible connections 85 therebetween, whereby said lift span is operated when said driving means is actuated and means for compensating for the variations in distance between the driving and driven means.

In testimony whereof I affix my signature.
ERNEST E. HOWARD.
